UNITED STATES PATENT OFFICE.

ALBERT HERMAN CLAUS, OF PORTLAND, OREGON.

ATTACHMENT FOR CLOTHESPINS.

Application filed May 15, 1923. Serial No. 639,172.

To all whom it may concern:

Be it known that I, ALBERT H. CLAUS, a citizen of the United States, and resident of Portland, in the county of Multnomah and State of Oregon, have invented certain new and useful Improvements in Attachments for Clothespins, of which the following is a specification.

My invention relates generally to improvements in clothes pins, more particularly to an attachment for clothes pins for suspending clothes pins and the article engaged thereby from a line, and it consists in the combinations, constructions and arrangements herein described and claimed.

An object of the invention is to provide an attachment which is adapted to be removably secured to a clothes pin and which affords facilities for releasably attaching the clothes pin to a line, whereby the article to be suspended from the clothes pin may be attached to the clothes pin and the latter then suspended from a line or removed from the line without there being any necessity of further manipulation of the article holding portion of the clothes pin.

A further object of the invention is to provide an attachment of the character described which is of simplified construction and adapted to be applied to clothes pins of various known types of construction.

Other objects and advantages will be apparent from the following description, considered in conjunction with the accompanying drawings, in which—

Figure 1 is a perspective view showing a clothes pin equipped with a practical embodiment of the invention and suspended from a line.

Figure 2 is a side elevation illustrating the manner of manipulating the article gripping portions of the clothes pin after the latter has been equipped with an attachment embodying the invention.

Figure 3 is a perspective view illustrating the manner of removably securing the attachment to one of the members of the clothes pin shown in the preceding views, and

Figure 4 is a perspective view showing a clothes pin which is adapted to be equipped with the attachment.

In the drawing, I show a clothes pin comprising cooperative similar members 1 and 2 respectively, each of which includes a handle portion 3 and a jaw portion 4. The

members 1 and 2 are hingedly connected intermediate their ends in the usual manner by a spring connector 5 having end portions 6 and 7 respectively pressing against the rear surfaces of the jaw members 4 and thus tending to hold the jaws closed.

The parts described so far are of ordinary construction and form no part of my invention except in so far as they cooperate with the parts which will be hereinafter described.

As is well known, a clothes pin having the construction described or any other usual construction is engaged with the article to be supported thereby at the time the clothes pin is attached to a line, such as that indicated at 8 in Figure 1. The clothes pin must be engaged with the line and with the article to be supported simultaneously for the reason that the line and a portion of the article to be supported must be clamped together between the jaws 4-4 of the clothes pin shown or between the corresponding portions of a clothes pin of any other well known type of construction. Since clothes lines ordinarily are supported in relatively elevated positions for obvious reasons, it will be manifest that such lines are ordinarily not readily accessible and that the work of attaching the clothes pins to the line and to the articles to be supported simultaneously cannot be accomplished conveniently and without raising the arms to strained and awkward positions, thereby causing considerable discomfort and fatigue to the operator, particularly when the weather is inclement.

In order to obviate the objectionable features of the ordinary type of clothes pin, such as the features just enumerated, my invention provides an attachment which is adapted to be removably secured to a clothes pin and which has means whereby it may be readily attached or removed from a clothes line without there being any necessity of manipulating the article engaging portion of the clothes pin at the time the latter is suspended from the line. To this end, an attachment embodying the invention may comprise a substantially U-shaped body or hook indicated generally at 9 which may be formed of an elongated strip of a material possessing inherent resiliency bent at a point somewhat nearer one end than the other end thereof to provide a relatively long shank 10 and a shorter bill 11. The shank 10 preferably is bowed outwardly or

toward the bill 11 intermediate its ends so that the bill and shank are located in close relation adjacent to the extremity of the bill, as indicated at 12, the extreme end portion of the bill being bent outwardly for the purpose of guiding the line 8 into the space between the bill and shank.

The outwardly bowed shank 10 is provided intermediate its length with a pair of rearwardly extending attaching lugs 13-13, which preferably are integral with the shank and are adapted to embrace one of the article engaging members of a clothes pin, which may be one of the members 1 and 2, whereby the shank 10 will be held in contact adjacent to its ends with the rear face of the said one article engaging member of a clothes pin.

From the foregoing description of the various parts of the device, the operation thereof may be readily understood. The articles which are to be suspended from a line through the agency of clothes pins equipped with an embodiment of the invention may be attached to the clothes pins conveniently before the latter are attached to the line. For example, in inclement weather, the articles may be attached to the clothes pins while the operator is sheltered from the weather. The articles with the clothes pins attached may then be suspended from the line 8 by hooking the bill of the attachment over the line. Since the shank of the attachment bows outwardly with respect to the clothes pin to which it is secured, and engages at its ends with the clothes pin, the stress placed on the latter because of its connection with the hook which is suspended from the line will tend to hold the clothes pin against movement in the direction of its length relatively to the supporting hook. If desired, the article supported, the clothes

pin and the hook attachment may be removed as a unit from the line or the article may be detached from the clothes pin without removing the clothes pin and hook from the line.

Obviously, my invention is susceptible of embodiment in forms other than that illustrated in the accompanying drawing and I therefore consider as my own all modifications and adaptations of the form of the device herein described which fairly fall within the scope of the appended claims.

Having thus described the invention, what I claim is:

1. As an article of manufacture, an attachment comprising a substantially U-shaped body made of a material possessing inherent resiliency, one of the members of said U-shaped body being relatively long and having intermediate its length a pair of cooperative attaching elements adapted to embrace a portion of a clothes pin to secure said U-shaped body to the clothes pin, said longer member of the U-shaped body being bowed intermediate its length toward the second member of the U-shaped body.

2. As an article of manufacture, an attachment comprising a substantially U-shaped body made of a material possessing inherent resiliency, one of the members of said U-shaped body being relatively long and having intermediate its length a pair of cooperative attaching elements adapted to embrace a portion of a clothes pin to secure said U-shaped body to the clothes pin, said longer member of the U-shaped body being bowed intermediate its length toward the second member of the U-shaped body, and the second member being bent outwardly at its extreme end portion.

ALBERT HERMAN CLAUS.
